(57) **CLAIM**

The ornamental design for a handle for cleaner, as shown and described.

DESCRIPTION

FIG. 1 is a perspective view of a handle for cleaner, showing our new design;

FIG. 2 is a front view thereof;

FIG. 3 is a rear view thereof;

FIG. 4 is a side view thereof;

FIG. 5 is another side view thereof;

FIG. 6 is a top view thereof;

FIG. 7 is a bottom view thereof; and,

FIG. 8 is another perspective view thereof.

The broken lines illustrating portions of the handle for cleaner form no part of the claimed design.
